DUPLEX ADDING MACHINE

Walter A. Anderson, Rockford, Ill., assignor, by
mesne assignments, to Underwood Elliott
Fisher Company, New York, N. Y., a corpora-
tion of Delaware

Application January 6, 1933, Serial No. 650,394

13 Claims. (Cl. 235—60)

This invention relates to two-totalizer or duplex adding machines. Among the salient objects of the invention are to provide for automatically placing both totalizers in use for addition; for automatically selecting one of the totalizers for totaling; for manually selecting the other totalizer for totaling; and for automatically taking the total from whichever totalizer has been selected for totaling.

10 In the accompanying drawings:

Figure 1 is a fragmental right-hand side elevation of one form of machine embodying my invention, the parts being shown in the position occupied after a blank or spacing cycle of operations has been performed, and the upper totalizer being conditioned for the taking of a total.

Fig. 2 is a fragmental plan view of the stop-setting mechanism and the spacing-stroke-enforcing mechanism.

Fig. 3 is a fragmental perspective view of some of the parts shown in Fig. 2.

Fig. 4 is a fragmental perspective view of the totalizer-selecting mechanisms and the keyboard lock.

Fig. 5 is a fragmental left-hand side elevation of the machine.

Figs. 6, 7 and 8 are detail views of certain parts shown in Fig. 5.

30 Fig. 9 illustrates a specimen of work produced on the machine.

In the embodiment herein shown of the invention, the keyboard, the stops and stop-setting mechanism, the blank-cycle-enforcing mechanism and the printing mechanism are similar to those fully disclosed in the Sundstrand Patent No. 1,583,102 dated May 4, 1926. This patent shows a machine having a single totalizer or register for accumulating amounts additively.

40 The present machine has two totalizers, together with means for selecting either totalizer for total-taking purposes, and in these respects it is similar to the machine shown in the Sundstrand application Serial No. 236,575 filed November 29, 1927

45 (now Patent No. 1,946,505, dated Feb. 13, 1934). In that application, however, either or both of the totalizers may be used to accumulate amounts either additively or subtractively, whereas in the present machine direct subtraction cannot be performed, and both of the totalizers are always used in item-entering operations.

50 In the drawings, 2 denotes the platen, and 3 the vertically reciprocatory type bars; 19 are two levers pivoted at 20 and connected through links 55 23 to two crank arms 25 (only one of which

crank arms is shown in the present drawings); 26 is the main rock shaft to which said crank arms 25 are secured; 27 is a handle for actuating the machine (it being understood that a motor may be used, if desired); 42 are the stops for 5 limiting the upward movement of the type bars in item-printing or adding operations; and 46 are the pins connected to the type bars and arranged to be arrested by said stops. The pins 46 are guided for vertical movement in a slide 47 10 which is movable transversely of the machine.

Means is provided to enforce the performance of a blank or spacing cycle of operations prior to the taking of a total. This means comprises a detent plate 48 (Figs. 1 and 2) guided to move 15 forward and back in a horizontal plane, said plate being connected through a bar 49 (Figs. 1 and 4) to a frame 50. The frame 50 is mounted to swing on the axis 51 (Fig. 1) and is normally impelled forward by springs 52 (only one of which is 20 shown in the present drawings).

A plate 53 (Fig. 3) pivoted in the machine frame at 54 is provided with a lug 55 at its lower edge. A lug 56 on the detent plate 48 is continually held in contact with the lug 55 through 25 the action of the springs 52. Whenever a numeral key is depressed to set up the first digit of an item, the detent plate 48 is pushed back into position to prevent the pins 46 from rising. This result is effected by means comprising a lever 57 30 pivoted in the framework at 58, one arm of which lever is arranged to engage the lug 55 and thus move the detent plate rearwardly into position to prevent the printing of a total. The other arm of said lever is arranged to be moved by a 35 universal bar 59 which is arranged to be moved counterclockwise, as viewed in Fig. 2, whenever a numeral key is depressed. The connections between the numeral keys and the universal bar 59 40 may be similar to those fully disclosed in said Patent No. 1,583,102.

The detent plate 48 is held in its rearward position against the force exerted by the springs 52 by means of a latch 60 (Fig. 3) pivoted at 61 and having a V-shaped tooth 62 which is held 45 in contact with the plate 53 by means of a contractile spring 63. When the lever 57 is operated in the setting up of the first digit of an item, the plate 53 is forced rearwardly of the point of the tooth and is held there by the pressure of the latch.

In order to remove the detent plate 48 from its effective position during the blank or spacing cycle, the following means is provided: The plate 55 53 carries a lever 64 pivoted at 65 and having a

projection 66 adapted to be struck by a projection 67 on the arm 25 fixed to the main rock shaft 26 of the machine. When the projection 66 is struck by the projection 67, the plate 53 is forced forward and away from the detent plate 48, thus releasing the latter to the action of the springs 52. In order that the projection 67 shall not release the detent plate 48 to the action of the springs 52 during the printing of an item, but shall release the detent plate only during the blank or spacing cycle, the projection 66 is made movable into and out of the path of movement of the projection 67. An arm 68 of the lever 64 is arranged to abut a lug 69 on the slide 47. A contractile spring 70 tends to move the lever 64 in the direction to lower the projection 66 out of the path of movement of the projection 67. When the slide 47 is in its initial position, the projection 66 is held up in the path of movement of the projection 67. When a digit is set up by the depression of a numeral key, the resulting movement of the slide 47 causes the projection 66 to be lowered out of the path of movement of the projection 67. When the slide 47 is returned to its initial position (as it is before a total is to be printed), the projection 66 is raised into the path of the projection 67, and is struck by the projection 67 during the next cycle of operations as described in Patent No. 1,583,102, page 5, lines 50-62, thus conditioning the machine for the taking of a total in the following cycle of operations. The movement of the detent plate 48 into its forward position to allow the pins 46 to rise also places the pawl 70^a (Fig. 1) in position to allow the totalizer to remain in mesh with the racks during the upward movement of the latter. As will be understood from Figs. 1 and 4, the forward movement of the detent plate 48 results in forward movement of the swing frame 50, the latter having a pin 70^b that lies in a slot in an arm 70^c pivoted at 70^d, the end of said arm being arranged to tilt the pawl 70^a out of effective position and into the total-taking position shown in Fig. 1. The parts 50, 70^a, 70^b and 70^c are old in the Sundstrand adding machine.

Referring now to the totalizers:

Each of the vertically reciprocatory type bars has a pair of racks 71 and 72 attached thereto. 73 and 74 are totalizers or registers arranged to be rotated by the racks 71 and 72, respectively, these totalizers being referred to hereinafter as the A totalizer and the B totalizer respectively. Each totalizer consists of a series of pinions rotatable upon a transverse shaft 75. The shafts 75 are supported for sliding movement to carry the totalizers into and out of engagement with the racks. The totalizers are so moved by means including links 76 and 77 pivoted at their rear ends to levers 78 and 79 pivotally supported in the machine frame, and two links 80 and 81. In the forward end of each of the links 80 and 81 is an elongated opening 82 to receive a headed stud 83 on a slide 84. Said slide is suspended for reciprocation longitudinally of the machine, and is arranged to be reciprocated by means fully disclosed in said application Serial No. 236,575 to move the selected totalizer into and out of mesh with the racks to add or to take a final total. A spring 84^a tends to move the links 80 and 81 forward to place the levers 78 and 79 in upright position and thus place the totalizers in neutral or idle position. The spring 84^a is anchored at one end to a fixed point and is connected at its other end to a link 84^b which is pivoted to the links 80 and 81. The link 84^b merely

serves to communicate power from the spring 84^a to whichever link 80 or 81 is free to move forward.

When addition is to occur, two mechanisms come into operation, one to select the upper totalizer and the other to select the lower totalizer. The selecting mechanism associated with the upper totalizer comprises a camslide 85 mounted on the slide 84 for vertical adjustment. On the slide 85 are cam surfaces 86 and 87. When the slide 85 is in its upper or addition position, as shown in Fig. 1, it confines the forward end of the link 80 between itself and the stud 83 so as to compel said link to reciprocate with the slide 84, thus causing the upper totalizer to move into and out of mesh with the racks 71. When the slide 85 is in such upper position, the cam surface 87 is up out of the way of the link 81 so as not to interfere with relative movement between said link and the slide 84.

The means for adjusting the cam slide 85 comprises a lever 88 which is pivoted in the stationary framework at 89. Said lever carries a pin 90 that lies in a horizontal slot 91 in the cam slide 85. A spring 92 normally holds the lever 88 in the position shown in Fig. 1.

The means for bringing the lower totalizer into use when addition is to be performed comprises a member 93 having a portion adapted to be interposed between the lower stud 83 and a headed stud 94 on the link 81. The member 93 has a slot through which the stud 94 extends, said member being thus guided to move up and down. The lower end of the member 93 is pivoted at 95 to a crank arm 96 fixed on a shaft 97 which extends transversely through the machine frame. On the left-hand end of the shaft 97 is a device which virtually constitutes a yieldable crank arm, said device comprising a plate 98 (Fig. 5) fixed on the shaft and a plate 99 pivoted on the plate 98 at 100. A spring 101 is anchored at one end to the plate 98 and is connected at its other end to a pin 102 on the plate 99. The spring 101 normally holds the pin 102 against the adjacent edge of the plate 98, the plates 98 and 99 thus normally moving as a unit. In order yieldingly to hold the member 93 in either of its two positions and to complete its movement into said positions, I provide a pivoted spring-actuated detent 103 having a stud adapted to lie in either of two notches in the plate 98.

To the crank arm composed of the parts 98 and 99 is pivoted at 104 a link 105 which is guided for substantially vertical reciprocation. The link 105 is arranged to be moved up and down to bring the member 93 into and out of effective position by means including a bell crank (see Fig. 6) pivoted in the machine frame on the axis 106. Said bell crank comprises an arm 107 having an elongated opening 108 to receive a stud 109 on the link 105. The arm 107 carries a member having a yieldable cam surface 110 and a dwell 111 arranged for engagement by a stud 112 fixed on the left-hand lever 19.

The surfaces 110 and 111 are formed on one arm of a lever 113 (Fig. 7) which is pivoted to the arm 107 at 114. A spring 115 stretched between the other arm of the lever 113 and a pin 116 on the arm 107 normally holds said lever 113 with a stop portion 117 on said lever in contact with the pin 109. Rigid with the arm 107 is an upwardly extending arm 118 carrying a dog 119 which is yieldingly held against a stop lug 120 on the arm 118 by a torsion spring 121. On the adjacent lever 19 is a stud 122 to engage 75

the dog 119 in the downward movement of said stud. In the upward movement of said stud the dog 119 is free to yield to allow the stud 122 to pass without causing movement of the bell 5 crank 107—118.

It will be seen that the stud 122 is adapted to cause upward movement of the link 105 for the purpose of withdrawing the upper portion of the member 93 from between the studs 83 and 94, and that the stud 112 is arranged to cause downward movement of the link 105 for the purpose of inserting the upper portion of the member 93 between the studs 83 and 94 and thus causing the link 81 to move with the slide 84 and thereby bring the lower totalizer into use. However, the studs 112 and 122 must not be allowed to exercise control over the lower totalizer when a total is to be taken from the upper totalizer. Means is therefore provided to deprive the studs 20 112 and 122 of control of the lower totalizer, which means includes a latch 123 (Figs. 5 and 8) pivoted at 124 and adapted to engage a notch 125 in the link 105. The latch 123 is yieldingly connected to an operating rod 126 by means of 25 a spring 127 that tends to hold the latch against a collar 128 on the rod. The forward end of the rod 126 is pivoted on a stud 129 on an arm 130, which is pivoted at 131. A spring 132 tends to swing the arm 130 rearwardly so as to push the latch 123 away from the link 105. 133 is a slide bar that serves to restore the stops 42 to 30 initial position as fully explained in the Sundstrand Patent No. 1,198,487, dated September 19, 1916. Rigid with the arm 130 is an arm 134 having a cam portion 135 that is held depressed by a roller 136 on the slide bar 133 when the latter is in its forward position, this being the position occupied when a total is to be taken. When a digit is set up in the keyboard preparatory to 40 adding an item, the slide 133 is moved rearwardly far enough to withdraw the roller 136 from the cam portion 135, thus permitting the spring 132 to withdraw the latch 123 and thus allowing the movement of the arm 107 by the stud 45 112 to lower the link 105 to raise the member 93 to cause engagement of the lower totalizer, as well as the upper, for addition. At the first part of the cycle, stud 122 caused counter clockwise rotation of the arm 107 to the position shown 50 in Figure 5, to withdraw the member 93 from its operative position. Shortly thereafter, stud 112 engaged the cam surface 110 to restore the member 93 to its operative position.

When a total is to be taken the slide bar 133 55 is always in its forward position, hence the latch 123 is held against the link 105 in readiness to slip into the notch 125 during the blank or spacing cycle that precedes the total-taking cycle, and therefore the stud 112 is prevented from 60 raising the member 93 into operative position and the lower totalizer remains idle while the total contained in the upper totalizer is being printed. During such a blank cycle the counter clockwise movement of arm 107, caused by stud 65 122, raises the link 105 to the position shown in Figure 5, where the latch 123 drops into the notch 125. Continued operation of the machine brings the stud 112 against cam surface 110 as usual, but since the link 105 is now held against downward movement by the latch 123, the arm 107 70 is held stationary, causing the lever 113 to be rotated clockwise about its pivot 114, tensioning the spring 115.

Totals may be automatically taken from the 75 upper totalizer following the performance of a

blank or spacing cycle, that is to say, without the necessity of depressing a total key. The means whereby the detent plate 48 is placed in its forward or ineffective position during the latter part of the blank or spacing cycle of operations has 5 been explained, and it will therefore be understood that in a cycle immediately following a blank cycle, the type bars will be free to rise, and since the upper totalizer is then in mesh with the racks 71 and the lower totalizer is in idle 10 position, the total contained in the upper totalizer will be printed.

In the present embodiment of the invention, all totals are final totals. The means for withdrawing the counter from the racks just before 15 the latter descend (whereby to leave the pinions standing at zero) may be of any preferred construction, as, for example, that fully described in the Sundstrand application Serial No. 670,665 filed October 25, 1923 (now Patent No. 1,965,611, 20 dated July 10, 1934). Herein I have shown only a portion of such means, principally the lever 172, as reference may be made to said application for a full understanding thereof.

When a total is to be taken from the lower or 25 "B" totalizer, that totalizer must be placed in use and the upper or "A" totalizer must be rendered idle. These results are attained by moving the controlling slide 85 to its lower position (as shown in Fig. 4), wherein the cam surface 86 30 is down far enough to allow the spring 84a (Fig. 1) to draw the link 89 forward to place the lever 78 in vertical position, thereby placing the upper totalizer in neutral position. When the control slide 85 is in its lower position, said slide 35 confines the forward end of the link 81 between itself and the stud 83, thereby compelling the link 81 to reciprocate with the slide 84 in the cycling of the machine.

The means for placing the control slide in its 40 lower position comprises a "B" total key 137 having a stem 138 which is guided for vertical movement and which is normally held in its upper position by means of a spring 139. On the key stem 138 is a pin 140 (Fig. 1) that bears against 45 an arm 141 which is pivoted at 142. Rigid with the arm 141 is a downwardly extending arm 143 having a pin-and-slot connection with the forward end of a link 144. The rear end of the link 144 is slotted, as at 145, so that it may be guided 50 on the stud 89 for reciprocation. Rising from the link 144 is an arm 146 that bears against an adjustable stop 147 on the lever 88. It will be seen that as the "B" total key is depressed, the link 144 will be pushed rearwardly, thereby rocking 55 the lever 88 on its axis 89 and thus moving the control slide 85 into its lower position, as shown in Fig. 4. The slide 85 is held in such position by means herein shown as comprising a hooked arm 148 which is rigid with the arms 60 141 and 143 and which is swung into position above a pin 149 on the key stem 138 when the "B" total key is depressed. The latch arm 148 is held in such position by means of a latch finger 150 beneath which the forward end of the 65 arm 141 engages when the "B" total key is depressed. The latch finger 150 is fixed to the right-hand end of a rock shaft 151. To the left-hand end of the shaft 151 is fixed a finger 152 (Fig. 5) which is in position to be engaged by the roller 70 stud 136. A spring 153 tends to move the latch finger 150 into position to restrain the arm 141 after the latter has been depressed below the lower end of said latch finger. At the completion 75 of any cycle, the slide bar 133 is moved forward

far enough to disengage the latch finger 150 from the arm 141, after which the slide bar 133 moves rearwardly far enough to allow the spring 153 again to place the latch finger 150 in position 8 to restrain the arm 141 the next time said arm is depressed.

When the latch finger 150 releases the arm 141, a spring 154 (Fig. 1) draws the slide 144 forward, thus allowing the spring 92 to raise the 10 control slide 85 to its upper position and withdrawing the latch arm 148 from the pin 149, whereupon the spring 139 restores the "B" total key to its normal position.

Means is provided to prevent the "B" total key 15 from being depressed after an item has been set up in the keyboard and prior to the performance of a spacing or blank cycle of operations. The means herein shown for this purpose comprises a link 155 (Figs. 1 and 4) pivoted at its 20 rear end to the swing frame 50. The forward end of the link 155 is bent into vertical position to form a pin 156. The pin 156 extends up through a slotted guide 157 which is rigidly secured to the key stem 138, whereby the link 155 25 is guided to slide forward and back. An angular lug 158 rigid with the key stem 138 extends into position to overlie the upper end of the pin 156 when the swing frame 50 is in its rearward position, as it is after an item is set up in the keyboard and until near the end of a blank cycle of operations. It will thus be seen that the "B" 30 total key cannot be depressed to condition the "B" totalizer for the taking of a total until after a blank cycle of operations has been performed. 35 Near the end of a blank cycle of operations the swing frame 50 moves into its forward position, thus placing the pin 156 forwardly of the lug 158 so that the "B" total key may be depressed, as shown in Fig. 4.

40 Means is provided to prevent the keyboard from being used to set up a number in the machine after the "B" total key is depressed. The means herein shown for this purpose comprises elements well known in the Sundstrand adding 45 machine and includes a locking plate 159 (Figs. 1 and 4) mounted below the keyboard for reciprocation forwardly and rearwardly in the machine. In this plate is a slot 160 for each numeral key stem 161, only one of these key stems 50 being shown in the present drawings. Each key stem 161 has a lug 162 to overlie the locking plate 159 when said plate is in its forward position, as shown in Fig. 4, and thus prevent depression of the numeral keys. Fixed to the locking plate 159 is a stud 163 having a tapered 55 surface adapted to be engaged by a cam lug 164 on the lower end of the "B" total key stem 138. It will be seen that when the "B" total key is depressed, the locking plate 159 will be moved 60 into its forward position to lock the numeral keys against depression. It is thus impossible to add in only one totalizer, as the keyboard will become locked when the "B" total key is depressed in an effort to select the "B" totalizer 65 for use in addition, and to place the "A" totalizer in idle position.

A "B" total may be taken before or after an "A" total. If taking a "B" total first, a blank cycle is performed, after which the "B" total key is depressed and held latched down by the latch finger 150. The next cycle will then give the "B" total, the "B" total key being automatically released at the end of the "B" total cycle. When the "B" total key is thus released, the spring 92 restores the control slide 85 to the 75

position shown in Fig. 1, thereby placing the "A" totalizer in use. The next succeeding cycle will then give the "A" total.

If the "A" total is desired first, it will be obtained automatically after the spacing cycle, as 5 the "A" totalizer is the only one which is then in use, the "B" totalizer being held out of operation by the latch 123 that controls the interponent 93. After the "A" total has been taken, the "B" total may be taken in the next succeeding cycle by first depressing the "B" total key.

As hereinbefore stated, a total may be automatically taken from the upper or A totalizer after a blank cycle and without the necessity 15 of depressing a total key. In fact, there is no total key for the A totalizer. It will thus be seen that the present machine will give a total from the A totalizer by merely cycling the machine twice in succession. 20

The key 137 herein termed the "B" total key is in the nature of a totalizer-selecting key, rather than a total key, as it does not determine whether the engagement between the racks and the totalizer shall be of the adding or the totaling type. The detent plate 48 and the pawl 70^a are automatically placed in position to allow totals to be taken, as hereinbefore described, from whichever totalizer is selected. 25

It will be understood that various changes may 30 be made without departing from the spirit and scope of the invention as set forth in the appended claims.

I claim as my invention:

1. A computing machine having, in combination, an item-setting keyboard; two totalizers; means for actuating the totalizers in accumulating and totaling operations; and means for controlling the totalizers in accumulating and totaling operations, the last mentioned means including a control member having one position wherein it selects one totalizer and another position wherein it selects the other totalizer, means for automatically enabling said other totalizer when an item is set up, means for automatically disabling said automatic enabling means when no item is set up, and a key and connections for moving said control member into its second-mentioned position. 35

2. A computing machine having, in combination, an item-setting keyboard; two totalizers; means for actuating the totalizers in accumulating and totaling operations; and means for controlling the totalizers in accumulating and totaling operations, the last mentioned means including a control member having one position wherein it selects one totalizer and another position wherein it selects the other totalizer, means for automatically enabling said other totalizer when an item is set up, means for automatically disabling said automatic enabling means when no item is set up, manual means for selecting said other totalizer, and means to disable said manual means when an item is set up. 55

3. A computing machine having in combination, an item-setting keyboard, two totalizers, means for actuating the totalizers in accumulating and totaling operations, and means for controlling the totalizers in accumulating and totaling operations, the last mentioned means including a 70 control member having one position wherein it selects one totalizer and another position wherein it selects the other totalizer, means for enabling said other totalizer when an item is set up, means for automatically disabling said enabling means 75

when no item is set up, and manual means for operating said control member to select said other totalizer.

4. A computing machine having, in combination, an item-setting keyboard; two totalizers; means for actuating the totalizers in accumulating and totaling operations; and means for controlling the totalizers in accumulating and totaling operations, the last mentioned means including 10 a control member having one position wherein it selects one totalizer and another position wherein it selects the other totalizer, means for enabling said other totalizer when an item is set up, means for automatically disabling said enabling means 15 when no item is set up, means for selecting said other totalizer for a totaling operation, and means to prevent such selection of said other totalizer when an item is set up.

5. A computing machine, having, in combination, an item-setting keyboard; two totalizers; means for actuating the totalizers in accumulating and totaling operations, one of said totalizers being always in use in accumulating operations; and means for controlling the totalizers in accumulating and totaling operations, the last mentioned means including means for automatically enabling the other totalizer when an item is set up, and means for automatically disabling said automatic enabling means when no item is set up.

30 6. A computing machine having, in combination, an item-setting keyboard; two totalizers; means for actuating the totalizers in accumulating and totaling operations; and means for controlling the totalizers in totaling operations, the last mentioned means including means tending automatically to select one totalizer, manual means to select the other totalizer, and means to disable said manual means when an item is set up.

7. A computing machine having, in combination, an item-setting keyboard; two totalizers; means for actuating the totalizers in accumulating and totaling operations; and means for controlling the totalizers in accumulating and totaling operations, the last mentioned means including 45 a spring tending to select one totalizer and place the other totalizer out of use, means for enabling the other totalizer for an accumulating operation, manual means for selecting said other totalizer for a totaling operation, and means to disable said manual means when an item is set up.

50 8. A computing machine having, in combination, an item-setting keyboard; two totalizers; means for actuating the totalizers in accumulating and totaling operations; and means for controlling the totalizers in accumulating and totaling operations, the last mentioned means including a spring tending to select one totalizer and place the other totalizer out of use, means for automatically enabling the other totalizer when an item is set up, means for automatically disabling said automatic enabling means when no item is set up, manual means for selecting said

other totalizer for a totaling operation, and means to disable said manual means when an item is set up.

9. A computing machine having, in combination, an item-setting keyboard; two totalizers; 5 means for actuating the totalizers in accumulating and totaling operations; and means for controlling the totalizers in accumulating and totaling operations, the last mentioned means including a spring tending to select one totalizer and 10 place the other totalizer out of use, means for automatically enabling the other totalizer when an item is set up, and means for automatically disabling said automatic enabling means when no item is set up.

10. A computing machine having, in combination, an item-setting keyboard; two totalizers; means for actuating the totalizers in accumulating and totaling operations; and means for controlling the totalizers in accumulating and totaling operations, the last mentioned means including a spring tending to select one totalizer and 20 place the other totalizer out of use, and means for automatically enabling the other totalizer when an item is set up.

25 11. A computing machine having, in combination, an item-setting keyboard; two totalizers; means for actuating the totalizers in accumulating and totaling operations, one of said totalizers being always in use in accumulating operations; and means for controlling the totalizers in accumulating and totaling operations, the last mentioned means including means for automatically enabling the other totalizer when an item is set up.

30 12. A computing machine having, in combination, an item-setting keyboard; two totalizers; means for actuating the totalizers in accumulating and totaling operations; and means for controlling the totalizers in accumulating and totaling operations, the last mentioned means including 35 a control member having one position wherein it selects one totalizer only and another position wherein it selects the other totalizer only, a spring tending to move the control member into the first mentioned position, means for automatically enabling said other totalizer when an item is set up, means for automatically disabling said automatic enabling means when no item is set up, manual means for selecting said other totalizer for totaling, and means to disable said manual means when 40 an item is set up.

45 13. A computing machine having, in combination, two totalizers, one of which is always enabled for use when accumulating, a keyboard, means controlled by the entering of an item on 55 the keyboard for placing the other totalizer in use for accumulation, means for automatically enabling the first mentioned totalizers for totaling, and manual means for enabling the other totalizers for totaling and for rendering the first 60 mentioned totalizers ineffective.

WALTER A. ANDERSON.

CERTIFICATE OF CORRECTION.

Patent No. 2,068,650.

January 26, 193

WALTER A. ANDERSON.

It is hereby certified that error appears in the printed specification of the above numbered patent requiring correction as follows: Page 5, second column, lines 58, 60 and 61 respectively, claim 13, for the word "totalizers" read totalizer; and that the said Letters Patent should be read with these corrections therein that the same may conform to the record of the case in the Patent Office.

Signed and sealed this 11th day of May, A. D. 1937.

(Seal)

Henry Van Arsdale
Acting Commissioner of Patents.
